The ornamental design for a piano with skyline design, as shown and described.

DESCRIPTION

FIG. 1 is a front, right-side perspective view of the piano with the skyline design, with a lid of the piano in an open position.

FIG. 2 is a right-side perspective view thereof.

FIG. 3 is a rear, right-side perspective view thereof.

FIG. 4 is another rear, right-side perspective view thereof.

FIG. 5 is a rear view thereof.

FIG. 6 is a rear, left-side perspective view thereof.

FIG. 7 is an enlarged, partial, rear, right-side perspective view of an upper-right portion thereof.

FIG. 8 is an enlarged, partial, top, right-side perspective view of an upper-right portion thereof.

FIG. 9 is an enlarged, partial, rear perspective view of an upper-rear portion thereof.

FIG. 10 is another enlarged, partial, rear perspective view of an upper-rear portion thereof.

FIG. 11 is another enlarged, partial, rear, right-side perspective view of an upper-rear portion thereof; and,

FIG. 12 is an enlarged, partial, front, right-side perspective view of the upper-right portion thereof.

In FIG. 1, rectangle 12 (shown with broken lines) indicates the portion of the piano with the skyline design corresponding to the enlarged, partial view shown in FIG. 12.

In FIG. 2, rectangle 11 (shown with broken lines) indicates the portion of the piano with the skyline design corresponding to the enlarged, partial view shown in FIG. 11.

In FIG. 3, rectangle 7 (shown with broken lines) indicates the portion of the piano with the skyline design corresponding to the enlarged, partial view shown in FIG. 7.

In FIG. 4, rectangles 8 and 10 (shown with broken lines) indicate the portions of the piano with the skyline design corresponding to the enlarged, partial views shown in FIGS. 8 and 10, respectively.

In FIG. 5, rectangle 9 (shown with broken lines) indicates the portion of the piano with the skyline design corresponding to the enlarged, partial view shown in FIG. 9.

Features of the piano with the skyline design that are shown within areas with translucent fill and bounded by broken lines in FIGS. 1-11 are disclaimed and form no part of the design to be patented.
